UNITED STATES PATENT OFFICE.

PETER BREIDENBACH, OF KENTON, OHIO.

FORCE-PUMP.

SPECIFICATION forming part of Letters Patent No. 236,930, dated January 25, 1881.

Application filed April 6, 1880. (No model.)

To all whom it may concern:

Be it known that I, PETER BREIDENBACH, a citizen of the United States, residing at Kenton, in the county of Hardin and State of Ohio, have invented certain new and useful Improvements in Force-Pumps; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

My invention relates to improvements in force-pumps for which I have obtained Letters Patent of the United States under date of July 8, 1879, No. 217,328.

The object of the invention is to perfect the pump by making it more efficient, easier of operation and simpler in construction; and to that end this invention consists in a certain novel arrangement and construction of pump-brake combined with a platform and the piston-rod; and it further consists in a novel arrangement of the valves, as fully described hereinafter, and shown in the accompanying drawings, in which—

Figure 1 is an isometrical view of my improved pump. Fig. 2 is a top-plan view of the lower valve-case. Fig. 3 is a like view of the piston, and Fig. 4 a section on line $\alpha\alpha$ of Fig. 3. Fig. 5 is a vertical transverse section of the pump and platform, and Fig. 6 a plan view of the piston-valve casing.

Like letters of reference are employed in the above figures of drawings to indicate like parts wherever such may occur.

A is a platform, preferably made of metal, and having cast therewith or bolted thereto, at opposite ends, the bearing standard or brackets $a' a'$. The platform is further provided with an aperture, a^2 , in which the piston-rod or pipe coupled therewith reciprocates, and an aperture, a^3 , in which reciprocates the connecting-link of the pump-brake.

B is the pump-cylinder, open at its lower end, and provided with the lateral vertical water-passage b , arranged in the usual manner, and having at its lower and upper ends the inlet and outlet ports to admit water from the

valve-casing into the cylinder above the piston.

C is the induction-valve casing, bolted to the lower end of the pump-cylinder. It is provided with valve-ports and disk-valves $C' C^2$, 55 the former to draw water into and through the lateral chamber b into the cylinder B above the piston, and the latter to draw water into the cylinder below the piston. These valves are constructed and arranged precisely as described in the above-mentioned Letters Patent, except that I employ only two valves instead of four.

D is the hollow piston-rod, carrying the cylindrical piston-head D', provided with three 65 inlet-ports, $d d' d^2$, in its upper face around the hollow piston-rod D. The piston-head D' carries within it a valve-plate, E, provided with three valve-ports and disk-valves, $e e e$, 70 coaxial with, or practically conaxial with, the inlet-ports $d d' d^2$, to adapt the said valves to close said ports from within at each down-stroke of the piston and eject the water admitted by valves C^2 through the hollow piston-rod, returning to their seats at each upward 75 stroke, at which time the water admitted through ports $d d' d^2$ from above the piston-head is ejected through the hollow piston-rod, thus adapting the pump to eject water both ways—that is, at each upward or downward 80 stroke, as will be readily understood.

The valves and their respective chambers in the piston-head are constructed substantially like those described in my Letters Patent above mentioned, except that here I employ only three instead of four valves, and that the valve plate or casing E is so arranged and constructed as to enable me to dispense with the bridge-pieces employed to hold the valves in their chambers and prevent them from tilting or turning on edge and becoming inoperative. By an inspection of Figs. 5 and 6 it will be seen that the valve-casing E fits closely to the roof of the piston-head, and that the valve-chambers are so arranged as to guide the 95 valves properly to and from their seats in the valve-casing and the ports $d d' d^2$ in the piston-head D', the said valve-chambers opening into a central space, e^3 , or passage, from which the water passes to the hollow piston-rod D. 100

By this arrangement the construction of the valve-casing E is greatly simplified, while the operation of the valves is not impeded.

The pump-cylinder is provided with bearing or bolt flanges b', by means of which it is bolted to a bearing-plate, A', cast in one piece with the platform.

F F are two roller-bearings, bolted to the plate A' and provided with bearing-slots f, for the axes of two anti-friction rollers, G G, and a central opening or slot, f', of a diameter slightly greater than that of the roller-axes, through which the rollers may be readily inserted into the bearings and maintained in proper position, without further attachment, by the piston-rod D, which passes upward between the bearings and rollers and through the aperture a² of the platform, having the usual pump-nozzle connected to its upper end. By means of this arrangement of anti-friction roller-guides the piston-rod is always maintained in the line of the axis of the pump-cylinder, which is very important to the good operation of the pump, as any deviation of the piston-rod from the said line will cause the piston-head to bind within the pump-cylinder, and consequently require great power to work the pump and produce a corresponding wear of the parts.

To still further reduce the power required to operate this class of pumps, I employ the following novel arrangement and construction of devices:

I is a brake-lever, formed of the oblong open frame i, having at one end an arm, i', that is pivoted to the bearing-lug, post, or bracket a depending from and cast with or attached to one end of the platform A. At the opposite end the open frame i has two ears or lugs, i² i², between which is pivoted one end of the connecting-rod K, that passes through the platform-aperture a³, and is pivoted at its upper end to the outer end of the brake-arm L, pivoted near its rear end in the bracket-bearing a' of the platform. The brake or lever L has a weighted and socketed enlargement at its rear end for the reception of the brake-handle or hand-lever l, as shown, the parts, in practice, being so arranged and constructed that the weight end of the brake-arm L will counterbalance, or nearly so, the parts directly and indirectly connected therewith—that is to say, the connecting-rod K, the brake or oscillating lever I and its bearing-block M, and the piston-rod D. The latter passes through said bearing-block, and is held against movement therein by the set-screw m, the block M oscillating upon pivots or trunnions or set-screws m' m' in the open frame i of the brake-lever I.

Any one conversant with this class of apparatus will be able to see at a glance the advantages obtained by this novel arrangement of brake-lever and anti-friction roller-guide.

Another advantage in this improved construction of pump lies in the fact that the pump-cylinder need not necessarily be immersed in the water that is to be elevated, as I am enabled to locate the cylinder at least thirty feet above the level of the water and work the pump with as great facility and efficiency as if said cylinder were immersed. I am thus enabled to locate the cylinder in almost all cases immediately underneath the platform, and secure it thereto and obtain ready access to said cylinder at all times without descending into the well and raising the cylinder and its parts, and the pipes connected therewith, to the surface.

I am aware that it is not new to employ anti-friction rollers as guides for a pump-rod, nor that of employing a weighted brake-lever to counterbalance the weight of the operating devices of a pump. I am further aware that the use of a swivel or a pivoted bearing-block to operate the pump-rod or hollow piston-rod is also old, and I do not wish to claim them, broadly.

Having now described my invention, what I claim, and desire to secure by Letters Patent, is—

1. In a pump of the class described, the platform A, having the bearing-brackets or lugs a a' and a supporting-plate, A', for the roller-guides, and pump-cylinder and apertures a² a³, all cast in one piece, in combination with said pump-cylinder and its operating devices, as and for the purpose specified.

2. In a pump of the class described, the combination, with the supporting-plate A' of the platform A and the anti-friction rollers G, of the brackets F, having the horizontal slots f' for the roller-axes, and the vertical slots f² for the insertion or withdrawal of said rollers to or from their bearings, as set forth.

3. In a pump of the class described, the combination, with the platform A and plate A' and the brackets F, having horizontal slots f and the vertical slots f', of the anti-friction rollers G, the hollow piston-rod, and appliances to reciprocate the latter, all arranged to operate substantially as and for the purpose specified.

4. The combination, with the hollow piston-rod D, of the brake composed of the open frame I, provided with an extension or arm, i', and bearing-lugs i², the adjustable pivoted block M, connecting-rod K, lever L, and handle l, and the platform A, having bearing-brackets a a', all arranged to operate as and for the purpose specified.

In testimony whereof I affix my signature in presence of two witnesses.

PETER BREIDENBACH.
